SPRING CUSHION ASSEMBLY

Vito Asaro, Detroit, Mich., assignor to L. A. Young
Spring and Wire Corporation, Detroit, Mich., a
corporation of Michigan

Application November 9, 1946, Serial No. 708,902

10 Claims. (Cl. 155—180)

1

This invention relates to improvements in spring cushion assemblies.

In spring cushion assemblies comprising spring seat cushions and spring back cushions such as are used in automobiles there is a tendency for the seat cushion to spring away from the lower end or edge of the back cushion when the seat cushion is compressed and when the back cushion is under compression stresses whereby there is a decided tendency for the clothing of the occupant to work rearwardly below the back cushion causing discomfort to the wearer and wrinkling of the clothing.

The main objects of this invention are:

First, to provide a spring cushion assembly including a seat cushion and a back cushion in which the relative relation of the lower edge of the back cushion to the seat cushion is maintained under varying loads and under varying conditions or stresses.

Second, to provide a back cushion structure having substantial resilience and at the same time one in which the upholstery is maintained in taut or unwrinkled condition.

Third, to provide a structure having these advantages which is quite simple and economical in its parts and easily assembled.

Fourth, to provide a spring structure in which the upholstery is effectively supported throughout.

Objects relating to details and economies of the invention will appear from the description to follow. The invention is defined and pointed out in the claims.

A preferred embodiment of the invention is illustrated in the accompanying drawings, in which:

Fig. 1 is a fragmentary end view of a spring cushion assembly embodying the invention, parts being conventionalized for convenience in illustration, compressed positions of the seat and back cushions being indicated by dotted lines.

Fig. 2 is a fragmentary plan view of the back cushion with parts broken away to show structural details.

Fig. 3 is an enlarged fragmentary vertical section of the back cushion.

Fig. 4 is an inverted view of the rear frame.

Fig. 5 is an enlarged fragmentary view in section on the broken line 5—5 of Fig. 6.

Fig. 6 is an enlarged fragmentary perspective view illustrating details of the structure.

Fig. 7 is an enlarged perspective fragmentary view showing further structural details.

In the embodiment of the invention illustrated, the seat cushion 1 is conventionally illustrated. It may be of any suitable spring structure or spring cushion assembly and as its details form no part of the present invention they are not illustrated herein.

2

The rear or back cushion frame designated generally by the numeral 2 is formed of wire and comprises side members 3, 3, top member 4, and bottom member 5. Cross pieces 6 and 7 are provided to support the row of top springs 8 which are of the pocketed type, these springs being secured to the cross pieces 6 and 7 by suitable clips 9 so that the springs are supported in a forwardly projecting position.

The front border frame which is preferably of flat stock or stock of flat cross section comprises the top member 10, bottom member 11 and end members 12, the end members being conformed to the shape of the ends of the cushion.

The upholstery designated generally by the numeral 13 comprises the top cover 14, the padding 15 of which is arranged upon the reinforced mat 16 carried by a plurality of forwardly bowed spring units or elements 17. These elements 17 are disposed vertically and the elements illustrated comprise two strands of spring wire having longitudinally spaced members 18 of substantial length extending transversely of the length of the unit and disposed with the loops in opposed oppositely disposed relation. These strands have longitudinal reaches 19 between the loops arranged in side by side relation.

Continuous helical coil members 20 are coiled about the reaches 19 of the strands with coils thereof engaging the loops to prevent axial displacement of the coils.

The lower ends of these spring units or elements are bent rearwardly and upwardly to provide spring arms 21 of substantial length. The upper ends of the spring elements are secured to the front border frame member 10 of the front frame by means of the clips 22. The lower ends of the spring elements are secured at the angle or union of the spring elements with their spring supporting arms to the bottom frame member 11 of the front frame by means of the clips 23.

The spring arms are supported by the sheet metal cross bar 24 which extends between the side members of the rear frame in substantially spaced relation to the bottom of the rear frame. This cross bar 24 has a downwardly facing channel 25, the top flange 26 of which is clamped upon the laterally turned ends 27 of the arms 21—see Figs. 5 and 6.

The cross bar 24 has a forwardly and downwardly projecting flange 28 which constitutes a fulcrum for the spring arms 21 of the spring units. This flange has holes 29 therein through which the clips 30 are engaged to clip adjacent loops of the spring arms to the supporting bar or cross bar 24.

Braces or struts 31 having coils 32 at their upper ends are secured to the side members of

the rear frame. These braces extend forwardly and downwardly and are secured to the end members 12 of the front border frame by means of clips 33. The end members 12 are bowed outwardly to suitably shape the cushion to the particular installation and spring units 34 of the type described are connected at their outer ends to the end frame members by the clips 35 and at their inner ends to adjacent bends of the spring units by clips 36.

Helical tie members 37 connect adjacent loops of the spring members while helical coils 38 and 39 are provided to connect certain of the loops of the end spring elements to the end frame members.

The upholstery supporting mat 16 is reinforced by parallel strands of resilient wire 40. The mat rests upon the bowed spring elements. The bowed spring elements, that is, disregarding the rearwardly turned arms thereof, are of the type illustrated in the Clark Patent No. 2,314,923 issued March 30, 1943. They might be described as being of the zig-zag type and arranged in connected pairs. It will be understood that other forms or shapes of the zig-zag type of springs than those illustrated might be used.

With the upholstery supporting springs thus mounted and supported, when they are subjected to compressive stresses their lower ends swing rearwardly and downwardly as is indicated by dotted lines in Fig. 1. The result is that the relation of the lower end of the cushion to the seat cushion is maintained under varying load conditions. Further, the back cushion may be made very yielding or resilient and at the same time the upholstery is supported in taut or smooth position throughout the yielding movement.

I have illustrated and described the invention in a practical commercial embodiment thereof. I have not attempted to illustrate or describe various embodiments or adaptations which I contemplate as it is believed that this disclosure will enable those skilled in the art to embody or adapt the invention as may be desired.

Having thus described my invention, what I claim as new and desire to secure by Letters Patent, is:

1. A spring cushion assembly including a seat cushion and a back cushion associated therewith with the lower end of the back cushion overhanging the rear end of the seat cushion and closely adjacent thereto, the back cushion comprising a rear frame including a cross bar disposed in vertically spaced relation to the lower end of the cushion and having a downwardly facing channel at its upper edge and a forwardly projecting flange at its lower edge, a row of coiled springs mounted at the upper end of the rear frame to project forwardly therefrom, a front border frame comprising top, bottom and end members, the top member being supported by said coiled springs, a plurality of vertically disposed forwardly bowed spring units each comprising strands of spring wire having longitudinally spaced oppositely disposed loops therein of substantial length extending transversely of the length of the unit and having reaches between the loops disposed lengthwise of the unit in side by side relation, and a helical tie member threaded upon said reaches, the lower ends of said spring units being rearwardly and upwardly return bent to provide rearwardly and upwardly projecting springable arms for the lower ends of the units, the upper ends of the arms being se-

cured within said channel of said cross bar with the arms in supported fulcruming engagement with the edge of said flange of said cross bar and secured thereto, the upper ends of the spring units being secured to the top member of the front border frame, said spring units at the union thereof with their said arms being secured to the bottom front frame member, and upholstery arranged over and supported by said

10 spring units whereby simultaneous compressive stresses on the seat and back cushion act to maintain the lower end of the back cushion in adjacent relation to the compressed seat cushion.

2. A back cushion comprising a rear frame in-

15 cluding a cross bar disposed in vertically spaced relation to the lower end of the cushion and having a downwardly facing channel at its upper edge and a forwardly projecting flange at its lower edge, a row of coiled springs mounted at the upper end of the rear frame to project forwardly therefrom, a front border frame comprising top, bottom and end members, the top member being supported by said coiled springs, a plurality of vertically disposed forwardly bowed spring units each comprising strands of spring wire having longitudinally spaced oppositely disposed loops therein of substantial length extending transversely of the length of the unit and having reaches between the loops disposed lengthwise of the unit in side by side relation, and a helical tie member threaded upon said reaches, the lower ends of said spring units being rearwardly and upwardly return bent to provide rearwardly and upwardly projecting springable supporting arms for the lower ends of the units, the upper ends of the arms being secured within said channel of said cross bar with the arms in supported fulcruming engagement with the edge of said flange of said cross bar and secured thereto, the upper ends of the spring units being secured to the top member of the front border frame, said spring units at the union thereof with their said arms being secured to the bottom front frame member.

3. A back cushion comprising a rear frame in-

15 cluding a cross bar of sheet metal disposed in vertically spaced relation to the lower end of the cushion and having a downwardly bent flange adjacent its upper edge providing a downwardly facing channel extending longitudinally of the cross bar, a row of springs mounted at the upper end of the rear frame to project forwardly therefrom, connected top and bottom front frame members, the top member being supported by said coiled springs, and a plurality of vertically disposed forwardly bowed spring units having integral springable rearwardly and upwardly projecting supporting arms at their lower ends, the upper ends of the arms having laterally turned ends extending longitudinally of the cross bar in the downwardly facing channel thereof, upper ends of the spring units being secured to the top member of the front frame, the lower ends of said spring units being secured to the bottom front frame member.

4. A spring cushion assembly including a seat cushion and a back cushion associated therewith,

20 with the lower end of the back cushion overhanging the rear end of the seat cushion and closely adjacent thereto, the back cushion comprising a rear frame, top and bottom front frame members, the top member being spring supported, a plurality of vertically disposed forwardly bowed spring units each comprising strands of spring wire having longitudinally spaced oppositely dis-

posed loops therein of substantial length extending transversely of the length of the unit and having reaches between the loops disposed lengthwise of the unit in side by side relation and a helical tie member threaded upon said reaches, said units having rearwardly and upwardly projecting supporting arms at their lower ends mounted at their upper ends on the rear frame, the lower ends of said spring units being secured to the bottom front frame member, and upholstery arranged over and supported by said spring units whereby simultaneous compressive stresses on the seat and back cushions act to maintain the lower end of the back cushion in adjacent relation to the compressed seat cushion.

5. A back cushion comprising a rear frame, top and bottom front frame members, the top member being spring supported, and a plurality of vertically disposed forwardly bowed spring units each comprising strands of spring wire having longitudinally spaced oppositely disposed loops therein of substantial length extending transversely of the length of the unit and having reaches between the loops disposed lengthwise of the unit in side by side relation and a helical tie member threaded upon said reaches, said units having rearwardly and upwardly projecting supporting arms at their lower ends mounted at their upper ends on the rear frame, the lower ends of said spring units being secured to the bottom front frame member.

6. A back cushion comprising a rear frame including a cross bar disposed in vertically spaced relation to the lower end of the cushion and having a downwardly facing channel at its upper edge and a forwardly projecting flange at its lower edge, a front frame comprising a bottom member and a spring supported top member, a plurality of vertically disposed forwardly bowed spring units each comprising strands of spring wire having longitudinally spaced oppositely disposed loops therein of substantial length extending transversely of the length of the unit and having reaches between the loops disposed lengthwise of the unit in side by side relation, and a helical tie member threaded upon said reaches, the lower ends of said spring units being bent rearwardly and upwardly to provide rearwardly and upwardly projecting springable supporting arms for the lower ends of the spring units, the upper ends of the arms being secured within said channel of said cross bar with the arms in supported fulcruming engagement with the edge of said flange of said cross bar and secured thereto, the upper ends of the spring units being secured to the upper front frame member, the lower ends of said spring units being secured to the bottom front frame member.

7. A back cushion comprising a rear frame including a cross bar disposed in vertically spaced relation to the lower end of the cushion and having a downwardly facing channel at its upper edge and a forwardly projecting flange at its lower edge, a front frame comprising a bottom member and a spring supported top member, a plurality of vertically disposed forwardly bowed zig-zag spring elements, the lower ends of said spring elements being bent rearwardly and upwardly to provide rearwardly and upwardly projecting springable supporting arms for the lower ends of the spring elements, the upper ends of the arms being secured within said channel of said cross bar with the arms in supported fulcruming engagement with the edge of said flange

of said cross bar and secured thereto, the upper ends of the spring units being secured to the upper front frame member, the lower ends of said spring units being secured to the bottom front frame member.

8. A back cushion comprising a rear frame including a cross bar disposed in vertically spaced relation to the lower end of the cushion and having a downwardly facing channel at its upper edge and a forwardly projecting flange at its lower edge, and a plurality of vertically disposed forwardly bowed zig-zag spring elements, the lower ends of said spring elements being bent rearwardly and upwardly to provide rearwardly and upwardly projecting springable supporting arms for the lower ends of the spring elements, the upper ends of the arms being secured within said channel of said cross bar with the arms in supported fulcruming engagement with the edge of said flange of said cross bar and secured thereto.

9. A back cushion comprising a rear frame, a plurality of vertically disposed forwardly bowed spring units each comprising strands of spring wire having longitudinally spaced oppositely disposed loops therein of substantial length extending transversely of the length of the unit and having reaches between the loops disposed lengthwise of the unit in side by side relation and a tie member for retaining said reaches in side by side relation, the lower ends of said units being bent rearwardly and upwardly to provide rearwardly and upwardly projecting springable supporting arms for the lower ends of the spring units and being secured to said rear frame, and supports for the upper ends of said spring units whereby compression stresses on the spring units act to swing the lower ends of the spring units downwardly and rearwardly.

10. A back cushion comprising a rear frame, and a plurality of vertically disposed forwardly bowed spring units each comprising strands of spring wire having longitudinally spaced oppositely disposed loops therein extending transversely of the length of the unit and having reaches between the loops disposed lengthwise of the unit in side by side relation and a tie member for retaining said reaches in side by side relation, said units having springable rearwardly and upwardly projecting supporting arms at their lower ends, the arms being secured at their upper ends to said rear frame, the upper ends of the spring units being springably supported whereby rearward compression of the spring units acts to swing their lower ends downwardly and rearwardly.
